UNITED STATES PATENT OFFICE.

WARREN A. MORRIS, OF CINCINNATI, OHIO, ASSIGNOR TO THE RICHARDSON COMPANY, OF LOCKLAND, OHIO, A CORPORATION OF OHIO.

CONTAINER.

Application filed March 19, 1923. Serial No. 625,935.

To all whom it may concern:

Be it known that I, WARREN A. MORRIS, a citizen of the United States, and a resident of Cincinnati, in the county of Hamilton and State of Ohio, have invented certain new and useful Improvements in Containers, of which the following is a full, clear, and exact description, reference being had to the accompanying drawings, forming part of 10 this specification.

My invention relates to containers, of the character termed as self-locking, in which the closing flaps on one or more sides, have a structure which will cause them to interlock when pushed together.

There have been devices of the same self-locking character produced hitherto, but none in which so far as I am advised, all four flaps are positively engaged and locked.

It is the object of my invention to provide a container or box in which all four flaps lock together when pushed inwardly of the box in a predetermined arrangement.

It is also my object to provide in a container, for a handle device whereby the container may be used instead of a basket for a wide variety of purposes.

I accomplish my objects by that certain construction and arrangement of parts to 30 be hereinafter more specifically pointed out and claimed.

In the drawings:

Figure 1 is a perspective view of the container with the interlocking flaps disengaged.

Figure 2 is a like view of the container with the flaps closed.

Figure 3 is a perspective view on a smaller scale showing the other side of the box, in 40 which two of the flaps have been developed as a handle.

Figure 4 is a plan of one kind of blank from which my box can be made.

The box will be constructed in any usual 45 manner for making boxes. In the form illustrated I show a pasted paper board box, although the material is not an essential, since no substantial flexibility is required to accomplish the lock.

There is thus a body portion marked generally as 1, and end closing flaps 3, 4, 5, and 6.

The flaps 3 and 5 are formed in the usual manner for closing flaps, each being pref-

erably one half of the size of the opening, 55 and each having a notch 7 cut therein, this notch having a curved wall 7^a, and a straight wall 7^b. The curved walls are on the same side of the box, in each flap 3 and 5.

The flap 4 has a tapered formation terminating in an oval shaped piece 8, which is larger than the combined area of the two notches 7, chiefly in its lengthwise component. When laid down over the flaps 3 and 5, the outer wall of this oval shaped 65 portion will about lie beyond the straight walls 7^b of the notches 7.

The flap 6 has its general shape a tapering one, and terminates in a flaring triangular shaped portion 9 similar to a wide 70 fish tail, the outer wall of which will come not quite flush with the curved walls of the notches 7, and the tips of which extend across a greater area than the notches combined.

As a result of this structure, the four flaps, 75 may be arranged as shown in Figure 1, with the flaps 3 and 5 laid down as if closing the box, the flap 4 next laid down, and finally the flap 6 laid down over the three 80 others. The operator then pushes inwardly of the box on the assembly of flaps, with the result that the flaps 3 and 5 will swing

down, and away from each other, expanding the opening between the notches, and the 85 portions 8 and 9 of the flaps 4 and 6 will slip through the space left between the notches.

A release of the pressure will result in the flaps coming back to normal closed position with the tips of the portion 9 caught under 90 the inner walls of the notches, and the portion 8 caught under the portion 9. The portions 8 and 9 are thus bent down slightly through the opening of the notches, and cannot be withdrawn laterally or upwardly, because their greatest dimensions are greater than the openings left for them to pass through.

The way to open this structure is to push 95 the flaps back in again, and break up the 100 interlocked relation.

Referring to the flaps at the other side of the box, it will be noted (Fig. 3), that the flaps 20 and 21 are formed as usual in boxes of the character selected for illustration and 105 that the two remaining flaps 22 and 23 are formed longer than necessary and have score lines 24, defining an extra extension 25

on each flap. In these extensions, I form a wide slot 27 or (if desired) a series of finger holes, so that when the extensions 25 are turned upwardly alongside of each other, as in the drawings, the two slots serve as fingers holes, by which the user may carry the box.

If desired the flaps 25 may be omitted and hand holes 30 formed in the container flaps 10 22 and 23, so that the box may be carried in two hands. One advantage of this last form is that the flaps 22 and 23 can be turned in when closing the box for shipment and will leave on unbroken surface exposed, as 15 formed by flaps 20 and 21.

It will be of interest to note that this structure was designed primarily for use of market gardeners. The box is designed to be shipped flat, with the tubular body portion 20 laid flat and the flaps extended out in line with the body. The gardener will erect the box by opening out the body, and arranging the bottom flaps into interlocked relation as shown. He will then place his 25 goods into the box, and close the top thereof to serve as a protection to the goods, and as a handle.

The boxes can be made in this style to hold exactly a bushel, half bushel, peck, or 30 the like, and plainly printed as such. They will be easier to handle than a bushel or half bushel basket, and in my opinion easier than any basket, and can be made very much cheaper. In degree of protection given to 35 the goods in the market wagon, delivery wagon, customers' hands or the like, it is of course far superior to a basket. The problem of storage of baskets is also solved, as these boxes can be laid flat when not in 40 use. Also they may be made strong and durable, and will last as long as required.

The invention in its several aspects is also applicable to many other uses, and it does not have to be in the form of a knock-down box. To illustrate a method of manufacture of a knock-down form of pasted 45 paper board box I have shown a blank in Figure 4. In this blank, the sections *a*, *b*, *c*, and *d* form the body portion of the completed box, and the flap *e* is stitched as indicated by dotted lines *f*, to the other end 50 of the blank, making thereof a tubular con-

struction, with cross score lines *g*, defining four side walls.

Along one side of the box are the flaps 55 3, 4, 5 and 6 and at the other are the flaps 20, 21, 22 and 23, constructed, as shown in the other views and as described above. Lengthwise score lines *g* define the lines of fold for the flaps with relation to the body. 60 The score lines 24 are also shown.

Having thus described my invention, what I claim as new and desire to secure by Letters Patent, is:—

1. In a box formed of fibre board or the like, the combination with a body portion forming side walls thereof, of four opposed bottom flaps articulated to the body portion, one set of opposed pairs of said flaps having cut-out portions in their ends, said cut out portions arranged to register with each other to form a continuous aperture across the interior of the box when said two flaps only are folded in thereover, the other set of opposed flaps having wing 75 shaped extensions adapted to fit within the aperture when in compressed position within the box, and to lock within the aperture when said first named flaps are withdrawn to right angled position with respect to the 80 side walls of the box.

2. In a box formed of fibre board or the like, the combination with a body portion forming side walls thereof, of four opposed bottom flaps articulated to the body portion, one set of opposed pairs of said flaps having cut-out portions in their ends, said cut out portions arranged to register with each other to form a continuous aperture across the interior of the box 85 when said two flaps only are folded in thereover, the other set of opposed flaps having wing shaped extensions adapted to fit within the aperture when in compressed position within the box, and to lock within 90 the aperture when said first named flaps are withdrawn to right angled position with respect to the side walls of the box, and means for forming a handle of the flaps at the upper end of said box whereby said 100 box may be used as a substitute for a market basket or the like.

WARREN A. MORRIS.
